SWITCH FOR MOTOR CASING

Hugh W. Batcheller, Newton, Mass., assignor to
Standard Mfg. Co., Worcester, Mass., a corpora-
tion of Massachusetts

Application September 18, 1936, Serial No. 101,424

1 Claim. (Cl. 200—155)

This invention relates to improvements in electric switches and more particularly to small size snap switches.

It is an object of the invention to provide a switch adapted to be mounted in an aperture in the casing of a motor such as may be employed for driving a small fan or the like. It is a further object of the invention to construct and arrange the parts of the switch in such a manner 10 as to facilitate rapid assembly of the parts without the use of special tools. It is a further object of the invention to simplify the structure of the individual parts so as to minimize the cost of production.

15 Further advantageous features will be apparent from the description of the invention which follows and from the illustration thereof on the drawing of which

Figure 1 is an exploded perspective view of a 20 switch embodying the invention.

Figure 2 is a plan view of an assembled switch.
Figure 3 is a bottom plan view of the same.

Figure 4 is a section on the line 4—4 of Figure 2.
Figure 5 is a section on the line 5—5 of Figure 2.

25 Figure 6 is a perspective view of a motor casing on which is mounted a switch similar to that illustrated in Figures 1 to 5.

As shown in Figure 1, the switch includes a hollow box-shaped metal housing member 10 having 30 in the end wall 12 thereof a circular aperture 14 through which projects the stem of a rotatable operating member 16. The outer end of the stem is preferably in the form of a knurled finger-piece or knob 18 to facilitate rotation of the operating member. At the inner end of the member 16 is a radial flange 20 having a pair of diametrically opposed notches 22. The forward face of the flange 20 is provided with one or more lugs 24, four such lugs being employed on the structure 35 illustrated. These lugs are adapted to enter simultaneously into a number of depressions 26 in the inner face of the end wall 12, such depressions being conveniently formed by denting the end wall 12 as indicated in Figure 1. The 40 notches 22 in the flange 20 are adapted to receive end portions 30 of a bridging conductor 32 which extends diametrically across the inner end of the member 16. These end portions 30 are bent up at right angles to the central portion of 45 the conductor 32 and engage in the notches 22 so that the conductor 32 rotates with the member 16 when the latter is turned. The lugs 24 and the grooves 26 are so related to the conductor 32 and the contact points with which it engages 50 that the member 16 is yieldingly retained in an

“on” position or in an “off” position. The lugs 24 are yieldingly pressed against the inner face of the end wall 12 by a spring 34 which is contained in a bore 36 in the inner end of the member 16, the other end of the spring bearing against the conductor 32 and pressing it against a plate or shield 40 of insulating material which presents a plane surface toward the operating member. This plate has a pair of apertures 42 therein through which are exposed elevated portions 44 of metal strips 46 which are mounted on an insulating base 50. This base is engaged by the rim of the housing member 10 to complete an enclosure within which the working parts of the switch are contained. The margins of the base project beyond 10 the sides of the member 10. In order to hold the parts in assembled relation, two of the side walls of the housing member 10 are provided with ears 52 which project through narrow slots 54 in the base 50. The projecting end portions 56 of 20 the ears 52 are then twisted, as shown in Figure 3, through a sufficient angle to prevent retraction of these end portions through the slot 54. The insulating shield 40 is preferably long enough to extend beyond the slots 54 when the 25 shield is in place against the forward face of the base 50. The ends of the shield 40 are notched as at 58 to receive the ears 52. Thus the ears serve to keep the shield 40 in its proper position 30 with the openings 42 fitting over the elevated portions 44 of the conductors 46. In order to ensure good contact between the bridging conductor 32 and the exposed portions 44 of the conductors 46, a pair of small bulges 60 may be formed on the conductor 32 in such positions as 35 to engage the exposed portions 44 when the switch is in the “on” position. When the switch is in the “off” position, the bulges or contact elements 60 ride on the face of the insulating shield 40.

The conducting strips 46 are easily and simply 40 made from flat strip stock, one end portion of each strip being bent into hook form so as to engage over the side of the base 50 as at 62, this side of the base being notched, as indicated in Figures 1 and 3, to hold the strips 46 against lateral displacement from their correct position. The other end portions 64 of the strips 46 are bent at right angles to the central portion so as to fit in corresponding notches in the other side edge of the base 50. These end portions 64 of the conducting strips may be notched as at 66 or otherwise treated to facilitate connection with suitable wires from the motor or other electrical appliance with 50 which the switch is to be used.

Figure 6 illustrates a small motor casing show- 55

ing a switch mounted thereon. For this purpose, the motor casing is made in two cup-shaped halves, each half being notched as at 70 to fit a portion of the housing member 10. Within the 5 casing is fixed a lining element 72, this element being slightly spaced from the inner wall of the casing at certain points. The liner 72 is also notched to receive the housing member 10. In order to hold the switch in place, two of the side 10 walls of the housing member 10 may be provided with lugs 78 struck out therefrom. These lugs engage the outer face of the liner 72 to support the switch against movement into the casing. The inner face of the liner 72 is engaged by the 15 end portions of the insulation sheet 40 which, with the margins of the base 50, project beyond the sides of the housing member 10 and prevent outward movement of the switch. Thus the switch is firmly secured in place in the casing when assembled therewith.

The parts of the switch itself are readily assembled by thrusting the stem of the members 16 through the opening 14, inserting the spring 34 into the bore 36, pressing the conductor 32 against the outer end of the spring so that the end portions 30 will enter the notches 22 of the flange 20, and pressing the insulation sheet 40 and the base 50 against the parts previously assembled so that the ears 52 project through the slots 54. 25 The projecting end portions 56 of the ears 52 are then twisted by pliers or any other suitable tool, whereupon the switch is completely assembled. In order to mount the switch in a motor casing such as is illustrated in Figure 6, the slit may first 30

be connected to the lead wires by soldering the ends of the latter to the end portions 64 of the conductors 46. The switch is then pushed into the notch 70 of one portion of the motor casing, and the other portion is then pushed in place, splitting the assembly of the casing with the switch. 5

It is evident that various modifications and changes may be made in the specific structure herein shown and described as an embodiment 10 of the invention, without departing from the spirit or scope of the invention as defined in the following claim.

I claim:

In an electric switch, a metal housing member having an aperture and a plurality of depressions in its inner surface adjacent to said aperture, a base attached to said housing member, an operating member projecting through said aperture, said operating member having a flange 15 within the housing and lugs on said flange arranged to enter said depressions, said operating member also having a bore in its inner end and notches in the edge of said flange, a plane insulating surface on said base opposed to said operating member, a pair of conducting elements having surface portions flush with said insulating surface and connectible into a circuit, a bridging conductor consisting of a strip of metal having its ends bent up to engage in said notches, and a 20 compression spring within said bore pressing said lugs against said housing member and said bridging conductor against said plane surface. 25

HUGH W. BATCHELLER.
